UNITED STATES PATENT OFFICE.

ALFRED JOHN BALKWILL, OF WAKEFIELD, ENGLAND.

SLIDE-VALVE ARRANGEMENT FOR STEAM-ENGINE CYLINDERS.

SPECIFICATION forming part of Letters Patent No. 746,776, dated December 15, 1903.

Application filed August 28, 1898. Serial No. 728,768. (No model.)

To all whom it may concern:

Be it known that I, ALFRED JOHN BALKWILL, a subject of the Queen of Great Britain, residing at 6 Calder Vale road, Wakefield, 5 York, England, have invented certain new and useful Improvements in Slide-Valve Arrangements for Steam-Engine Cylinders, of which the following is a specification.

The object of my invention is an improved 10 slide-valve arrangement for steam-engine cylinders whereby with special ports and valve part of the steam after completing its work at one side of the piston traverses the valve to the opposite side of the piston, the remainder of the steam being exhausted. For the 15 purpose of my invention, in addition to the usual steam entry and exhaust ports in the valve-face of the cylinder, I provide another or branch port in the valve-face, but leading 20 out from one of the ordinary ports, this double port having only one port in the cylinder.

The slide is formed with an external chamber or port outside its ordinary exhaust-port for communication with the additional or 25 auxiliary port and the ordinary port on the opposite side for the passage of part of the steam from one side of the piston to the other.

The working of my improved slide-valve arrangement is as follows: The steam pushes 30 the piston down and at three-fourths stroke the slide-valve shuts the steam off. Then it expands slightly. Just before the piston gets at the bottom end steam passes round through the top side through the external port of the 35 slide-valve to the bottom side of the piston.

At a certain point the steam is shut off; but at the very instant it is shut off the remainder is exhausted to the atmosphere through the central port, thus allowing the transferred 40 steam to act expansively in aiding the return of the piston. On the return stroke the whole of the steam which had previously passed through the top to the bottom is exhausted. When the steam at the top side of the piston 45 is exhausted, there is only a slight exhaust, but on the downstroke there is a full exhaust. Although steam goes in at the top side, it is nearly all exhausted from the bottom side.

My invention will be clearly understood 50 from the accompanying drawings, in which each figure represents in section an engine-cylinder, slide-valve, and valve-casing.

Figure 1 shows the slide-valve in position, with the inlet-port slightly open for admission of live steam to the top part of the cylinder for commencement of piston-stroke, the exhaust-port being open to bottom of piston. Fig. 2 shows the slide-valve moved for the full admission of live steam to the top of the piston, the piston at this time having reached about one-third of its stroke. Fig. 3 shows the valve moved over to shut off the steam-inlet, the exhaust being fully open from opposite end of cylinder. Fig. 4 shows the piston at the end of its stroke and the ports and 65 supplementary passage in the valve open for the transfer of the used steam to opposite end of cylinder. Fig. 5 shows the position the valve and piston occupy when the steam-transference passage is cut off and the exhaust opened to the top part of the cylinder.

A is the cylinder; B, piston; C, cylinder-ports; E, ordinary exhaust; F, slide-valve; G, slide-valve casing; H, additional through-port in slide-valve F; I, branch port from port D 75 of cylinder A for partial exhaust; J, piston-rod; K, valve-rod; L, steam-supply pipe; M, usual exhaust-passage in slide-valve F.

The action is as follows, assuming the piston B to be at the top of its stroke, as indicated in Fig. 1: Steam enters valve-casing G by the pipe L and passes through the port C for exerting its power against the piston B until the piston B has traveled to about that portion of its stroke indicated in Fig. 3, at 85 which time the valve F will have been moved to close the port C to the entrance of live steam to the cylinder. The further expansion of the steam within the cylinder operates on the piston to complete the stroke. 90 As the piston is arriving at the end of the stroke the slide-valve is next moved back, as at Fig. 4, to bring the supplemental passage H of the slide-valve into communication with the ports C and D, so that a portion of the 95 used steam can pass through the channel thus afforded to the back of the piston B. Owing to the inertia of the moving parts of the engine the piston will now be started upon its return stroke. Before it reaches 100 the center of the cylinder, however, the valve F will have started toward the position shown in Fig. 5, gradually moving the passage H out of communication with either of the ports

C and D and placing the port C in communication with the exhaust E through port M. Thus the steam in front of the piston will escape through the exhaust to the outer air, so that the expansive power of the steam which has been "trapped," so to speak, at the rear of the piston may be utilized in moving the piston to the end of its return stroke. On the next movement of the slide-valve F, as at Fig. 1, the supplementary or additional port H is closed and the steam at the rear of the piston so used expansively passes through port D, branch I, and port M to the exhaust-passage E simultaneously with the inlet of a fresh charge of steam by the port C for a new power-stroke of the piston B.

What I claim, and desire to secure by Letters Patent, is—

In combination with a cylinder, a piston therein, a steam-chest associated with the

cylinder and provided with ports C and D leading into the cylinder near opposite ends thereof, with an exhaust-port located between said ports and with a branch port communicating with said port D, and a slide-valve in said steam-chest provided with a through-port for affording communication between the ports C and D, and with an exhaust-passage adapted to place said exhaust-port alternately into communication with said branch port and with the port C, the combination operating as described.

In testimony whereof I have hereunto set my hand in presence of two subscribing witnesses.

ALFRED JOHN BALKWILL.
